SHUTTLE

Karl A. Gelpke, Edgefield, S. C., assignor to Gelco Development Corporation, Canton, Mass., a corporation of Delaware

Application April 25, 1944, Serial No. 532,590

1 Claim. (Cl. 139—196)

1

The invention relates to loom shuttles in general, and more particularly to shuttles for weft-replenishing looms in which the supply of filling in the shuttle is replenished automatically by mechanical means forming a part of the loom.

A leading object of the invention is to reduce the weight of the shuttle while increasing or at least maintaining its capacity, its useful life, its convenience, and utility, and without substantially increasing its cost. Tests have indicated that in looms running at customary speeds using conventional wooden shuttles a decrease of one ounce in shuttle weight results in a corresponding saving of at least 1½% in the power required to drive the loom, in addition to the economies realized through lightening the load and the wear and tear on the pickers, binders, and other parts sharing in the picking and checking of the shuttle, and through the reduction of shock and vibration in the loom.

Refinements in the conventional wooden shuttle have been carried to the point where no further reduction in weight without corresponding loss of its essential qualities have been possible in working with this material, and metal shuttles as hitherto proposed have either been heavier than their wooden counterparts or have possessed other drawbacks which have prevented their entering into common use in fly shuttle cloth looms.

To attain its leading object, the invention provides a shuttle body made wholly from metal or metallic alloys of the class technically known as light metals, such as magnesium, magnesium alloys, Duralumin, and the like, and also designed to be fabricated by pressure die casting or forging to cut the complexity and cost of manufacture. The improved shuttle weighs from one to two or more ounces less than its wooden counterpart. Along with its lightness and the simplification of the manufacturing steps, the superior physical characteristics of appropriate metals or alloys of this class permit the shaping of the side walls of the shuttle in thin sections, thinner than practicable with wood, thus enabling an increase in the internal dimensions of the bobbin chamber so as to accommodate a bobbin wound to greater diameter and thus carrying more yarn for the same outside dimensions of the shuttle. Being made of metal, the shuttle cannot warp, and is devoid of any tendency to roughen, splinter, or split in use,

2

thus obviating entirely the commonest forms of shuttle failure which necessarily terminate the useful life of a wooden shuttle; even if deformed by an accident the improved shuttle is capable of being brought back into shape for further use, and it is made in two halves each comprising one entire side of the shuttle so that in the event of extreme wear or injury beyond repair an entire new side, made interchangeable with the worn half without need for machining or fitting, can be quickly and easily installed with retention of the unworn or undamaged half. Further, the discarded parts or shuttles have an important salvage value, by contrast with wooden shuttles, thus additionally reducing the cost to the mill.

For further economy, the shuttle is provided with self-threading devices or parts which are mainly or wholly integral with the material of the shuttle, thus saving a large part of the cost of making and fitting the usual self-threading attachment, as well as eliminating the possibility of this attachment working loose in use.

With the aim of overcoming the further drawbacks of the metal shuttles of prior types, the 25 reed-side of the shuttle is provided with a non-metallic surfacing, preferably of fiber or plastic, to minimize the wear of the shuttle by the shuttle box and also the abrading action produced on both the metal dents of the reed and the metal 30 of the shuttle which has rendered prior types of metal shuttles impracticable. The outward surfaces of the rest of the shuttle are subjected to a case hardening treatment to provide them with a wear-resisting surface. In addition, the entire 35 surface of the shuttle is provided with a color, coating or surface treatment producing a higher degree of heat radiation and dissipation than that of the normal untreated component metal, so that the very material degree of heat generated by 40 the shuttle in working will not be allowed to make the shuttle too hot to be handled by the loom attendant whenever necessary and without delay.

Other objects of the invention, and the manner of their attainment, are set forth hereinafter.

45 An illustrative embodiment of the invention is shown in the accompanying drawings, in which—

Fig. 1 is a plan view.

Fig. 2 is a rear elevation.

50 Fig. 3 is a view in horizontal section on line 3—3 of Fig. 2.

Fig. 4 is a partly sectional elevation on line 4—4 of Fig. 1, showing the rear half of the shuttle, the mounting of the bobbin jaws and guide, and the arrangement of the self-threading devices.

Fig. 5 is a view in horizontal section on line 5—5 of Fig. 2.

Fig. 6 is a vertical section on line 6—6 of Fig. 1.

Fig. 7 is a side elevation of the combined horn and thread hook when this member is formed separately from the parts of the shuttle.

Fig. 8 is a view of the same when viewed from the right-hand side of Fig. 7.

Fig. 9 is a section similar to Fig. 6 but showing only one-half the shuttle width, illustrating the case-hardened surfacing of the shuttle.

The improved shuttle is of conventional outside shape, dimensions, and contour, and comprises two main parts fabricated by pressure die casting or forging from any suitable moldable or castable metals or metallic alloys of specific gravity ranging from 1.70 to 1.90, the front side or half 1 which has the usual feeler slot 3 and longitudinal yarn groove 5, preferably cast or molded therein as this side is formed, and a rear side or half 7 which is formed with a straight surface throughout its entire length except adjacent the tapered end-portions 9. These end portions of both halves are given the usual or any preferred taper in the process of molding, but the rear half 7 is prolonged substantially beyond the length of the front half, and this prolongation 11 at each end of the rear half is given a conical shape and made to overlap and fit closely against a web 13 formed on each end of front wall 1. The conical projections 11 are shaped to continue accurately the conformation of the tapered end portions 9 of the shuttle, and thus form integral shuttle points for engagement by the loom pickers. Horizontal webs 15 extend inwardly at both ends of both halves, at the bottom of the shuttle, and at 17 at the top of the shuttle at the end thereof that is away from the self-threading devices, to meet in a vertical plane extending axially of the shuttle; these meeting edges 19 form the bearing surfaces between the two halves when bolted together by retaining bolts 21 put through countersunk holes formed in bosses 23, 25, provided on the inside of each half near each end thereof, and through countersunk steel nuts 22. A rounded lateral extension of the terminal web 13 at each end of the front half fits accurately within the hollow of the rear half adjacent the base of each conical projection 11 to aid in preventing relative vertical movement of the two halves. By reason of the close fit of the terminal web 13 of the front half against the base of projection 11, this part is adequately supported against the stress of the impact of the picker. The bottom surfaces of the webs 15 at the bottom of the shuttle are arched upward and inward toward their edges 19 to give clearance of these areas from the shuttle race.

The bosses 23 at the end of the shuttle remote from the delivery eye are elongated lengthwise and extend inward to grip tightly the shank 27 of the bobbin jaws 29, the latter being of conventional design and of usual steel construction, a spacer 31 being inserted between the two sides of the shank 27 and the bolt 21 passing through such spacer as it goes through holes provided in the shank so that the span of the jaws will not be altered when this bolt is drawn up tight. A bobbin-guide 33 of more or less standard shape and function is combined with the bobbin jaws, its horizontal arms 35 extending respectively

above and below the shank 27 and being permanently attached thereto by a rivet 37 put through aligned holes in these arms and fitting tightly within the space left between spacer 31 and the bend at the end of the shank 27.

To hold the bobbin jaws 29 against movement up and down about the bolt 21 as a center of gyration, the webs 15, Fig. 6, at the bottom of the bobbin are extended lengthwise to form shelves 10 engaging and supporting the bobbin jaws throughout the entire length of their curved shoulders and partway along the straight portions of their jaws, with other projections 39 formed on the inside wall of each half above the bobbin jaws to engage and hold down the bobbin jaws adjacent the curve of the shoulders. An appropriate rabbet is provided in each shelf 15 to receive and support the lower arm of the bobbin guide. Thus held, the bobbin jaws are much 15 more rigidly maintained against vertical gyration than in the conventional wooden shuttle, with consequent greatly reduced likelihood of the occurrence of a bobbin smash as a result of sending an upwardly protruding bobbin through the shed. 20 The metallic deck over the upper arm of the bobbin guide created by the upper webs 17 at this end of the shuttle effectively eliminates all chance of the guide or its conventional retaining screw as used in wooden shuttles working loose to extend 25 upward above the shuttle so that it can catch and break the warps.

As shown in the transverse section of Fig. 6, the upper and lower edges of the walls are thickened and extended inward slightly to form ribs or 30 flanges 41 which give the interior surfaces of these walls a hollow section imparting stiffness resisting the bending inward of these walls under the pressure of the binder or swell in the shuttle box, and the front wall 1 is also in certain instances 35 given a corrugated form in section by reason of the inward curvature of this wall made to provide additional metal for forming the yarn groove 5 on the exterior of this wall, this shaping aided by the flange outlining the feeler slot 3 at the 40 inside of the front wall imparting further stiffness. By reason of these special sectional shapes, combined with the physical characteristics of the light metals used, the walls are ordinarily only one-half as thick, and in all cases much thinner 45 than they can safely be made in wood, and hence the space within the shuttle is $\frac{1}{8}$ to $\frac{1}{2}$ inch wider and will take a yarn package having this amount of increased diameter, with corresponding lowering of doffer and battery hand and other costs to 50 the mill. The ratio of side-wall thickness to the width of the space between the walls defining the bobbin diameter is ordinarily around 1 to 11, in contrast with the usual ratio in wooden bobbins of from 1 to 4 up to 1 to 6.

55 The non-metallic facing strip 43 forming the wearing surface of the rear wall is ordinarily of uniform thickness throughout and formed with beveled or rabbeted margins, the strip being inlaid for approximately half its thickness in a sunken area 45 formed in the rear side of the shuttle. A slight bead 47 of metal formed in the molding operation outlines the sunken area, and after coating the inward surface of the strip with cement and pressing it into the sunken area, 60 this head is rolled or pressed into overhanging relation with the rabbeted or beveled edges all the way around the strip, thus fixing the strip securely in place. Preferably the strip extends partway of the taper at both ends of the shuttle, 65 to get the ends of the strip out of range of the

reed and the parts at the mouth of the shuttle box. However, the method of attachment is such that the strip can be replaced in case of damage, by proper manipulation of the retaining bead 47. In certain instances the strip is additionally secured to the rear wall by the use of soft copper rivets as indicated by the dotted circles 49. This strip stiffens and strengthens the rear wall of the shuttle, and enables it to be made thinner than the front wall.

The integral self-threading arrangements comprise an oblique web 51 on the rear half of the shuttle the edge of which is straight and slants forward from substantially at the median vertical plane of the shuttle to a point well in front of such plane, extending to the base of the projection forming the shuttle point 11. Beneath this web there is formed on the rear half a shoulder 53 having a roughly semi-circular hollow 55 which tapers and becomes shallower toward the adjacent end of the shuttle, and on the front half of the shuttle is formed a curving beak 57 tapering inwardly and downwardly toward the adjacent end of the shuttle and terminating in a thread-hook 59 which extends to the said median plane of the shuttle, and confronting the semi-circular hollow. Below the beak 57 there is formed on the front half a generally flat surface 61 which inclines downwardly in a direction away from the adjacent shuttle point, extending in spaced relation to the under side of the beak. The edge 65 of this flat surface nearest the eye 63 of the shuttle extends inwardly at substantially right angles to the shuttle axis for a certain distance, and then obliquely inward in a direction toward the adjacent end of the shuttle. The under side of the beak is correspondingly shaped to parallel these adjacent parts, so that a thread slot 67 is formed between the beak and the flat surface 61 which slot extends in a slanting direction down and away from the adjacent end of the shuttle, and then vertically down into the shuttle eye 63.

On the bolt 21 at this end of the shuttle is mounted a plate 69 of hardened steel or other hard metal having a sharp-pointed horn 71 which is located centrally upon the axis of the eye, and a guide surface 73 extending down to the inturned web 15 at the shuttle bottom, around which surface the yarn reeves in making a nearly right angle turn in its course to the eye. The plate 69 is clamped tightly between the boss 23 on the front half and the end of the much longer sleeve-like boss 25 on the rear half and surrounding the shank of the bolt. The upper edge of this plate is shaped to fit smoothly against the curving interior wall of the front half, and to be completely shielded from above by the overhanging rim of the front wall, so that the yarn cannot get caught between these latter parts. The end of the plate toward the bobbin is bent to extend transversely across the thread passage left between the rearward face of the plate and the parts on the rear half of the shuttle, and shaped to provide a rearwardly and downwardly curving hook 75, the web 77 below the hook diverting the yarn laterally to prevent its wedging between the end of the sleeve 25 and the adjacent face of the plate. When the shuttle is made of sufficiently wear-resisting metal, or alternatively when the guide surface 73 is formed by a hardened pin, the horn 71 and hook 75 are cast as integral parts of the front half of the shuttle, and the boss 25 on the rear half extends clear to the corresponding boss at the front half.

On the first pick of the shuttle following the automatic insertion of a fresh bobbin by the transfer mechanism of the loom into the grip of the bobbin jaws, with accompanying expulsion of the spent bobbin through the bottom of the shuttle, the yarn is drawn along the edge of web 51 and diverted to the end thereof nearer the shuttle point, the swirling of the unwinding yarn as it leaves the bobbin tip carrying it beneath the thread hook 75 and the end of beak

57. On the second pick, the yarn is diverted by the under surface of the beak down the slot 67 and into the eye 63, and slides down the inclined surface of horn 71 that is toward the adjacent shuttle end, thereafter rising into the notch behind the horn. During the continuance of the weaving, the yarn runs under the hook 75, over the boss or sleeve 25, through the notch and around surface 73, and out through the shuttle eye, in both directions of the shuttle's travel.
- 20 Any suitable known method of case hardening the specific metal chosen for the shuttle is used, provided that it does not render the metal brittle or otherwise impair the physical qualities needed in the shuttle. A specific form of surface hardening found satisfactory in use is that of the Dow Chemical Co., termed by them "Dow No. 6 hardening." A case-hardened outer skin is illustrated at 82 in Fig. 9.

30 The treatment of the metallic surfaces of the shuttle to radiate and dissipate heat therefrom includes a number of different techniques such as blackening or darkening the inside and outside surfaces as indicated at 78 in Fig. 1 by chemical coloring or tarnishing treatments, heat treatments, and application of pigmented adhesive coatings such as paints, enamels, and lacquers, or, as an alternative, mechanically grooving or pitting the surfaces as indicated at 80, Fig. 2, on a scale fine enough to extend the total radiating surface of the shuttle without roughening the shuttle exterior so that it will catch the yarns; it also includes the use of coatings or alloys subject to tarnishing upon exposure to the air alone, or to the humidified air commonly present in the mill, the alloy used being either the entire component material of the shuttle or a surface coating applied to the shuttle parts. A preferred treatment comprises a matte black finish

35 created on all surfaces, inside and out, of the shuttle by a chemical dipping treatment which results in the blackening of all exposed surfaces of the metal. Though this finish is superficial, only those parts on the bottom and sides of the

40 shuttle which are subjected to constant rubbing contact wear bright, leaving by far the greater part of the shuttle's surfaces black and possessed of increased heat-radiating power.

45 While I have illustrated and described a certain form in which the invention may be embodied, I am aware that many modifications may be made therein by any person skilled in the art, without departing from the scope of the invention as expressed in the claim. Therefore, I do not wish to be limited to the particular form shown, or to the details of construction thereof, but

50 What I do claim is:

55 A shuttle for automatic weft-replenishing looms comprising two halves respectively forming the front and rear walls of the shuttle and each wall cast from metal so as to have a relatively thick rim at its top and bottom edges and a relatively thinner web intervening between the runs of each wall, one of the halves being longer than

the other and provided at each extremity with a conical point, and the half forming the rear wall having a synthetic non-metallic surfacing for engagement with the loom reed.
